U.S. CL. 260—239

5 Claims

ABSTRACT OF THE DISCLOSURE

Compounds of the formula

wherein R' is hydrogen, alkyl up to 4 carbon atoms or phenyl; R'' is alkyl up to 4 carbon atoms, hydrogen, phenyl or benzyl; and R''' is alkyl up to 12 carbon atoms, alkoxy up to 12 carbon atoms, amino, monoalkylamino up to 4 carbon atoms, dialkylamino where alkyl is up to 4 carbon atoms, the aromatic radicals of phenyl, phenoxy, benzyl or benzoxy and substituted radicals where the substituent is alkyl up to 4 carbon atoms, alkoxy up to 4 carbon atoms, chlorine, bromine or nitro.

The compounds are prepared by the irradiation of conjugated vinyl azides with ultra-violet light in the range of 200 to 300 m μ .

These compounds are useful in inhibiting the growth of fungus.

This invention relates to a new class of chemical compounds and a novel procedure for their preparation. More specifically, the invention is directed to the preparation of chemicals useful in inhibiting the growth of fungus.

It has been found that the ultraviolet irradiation of conjugated vinyl azides will induce a rearrangement to the azirene structure. The useful conjugated vinyl azides are described and claimed in copending application Ser. No. 517,488, filed Dec. 29, 1965, by George R. Harvey.

The novel reaction by which the new compounds are formed follows the equation:

wherein R' is selected from the class consisting of hydrogen, alkyl of up to four carbon atoms and phenyl; wherein R'' is selected from the class consisting of alkyl of up to four carbon atoms, hydrogen, phenyl and benzyl; and wherein R''' is selected from the class consisting of alkyl of up to twelve carbon atoms, alkoxy of up to twelve carbon atoms, amino monoalkylamino wherein the alkyl moiety has up to four carbon atoms, dialkylamino wherein both alkyl moieties have up to four carbon atoms; the aromatic radicals consisting of phenyl, phenoxy, benzyl, benzoxy, and the said radicals containing substituents selected from the class consisting of alkyl of up to four carbon atoms, alkoxy of up to four carbon atoms, chlorine, bromine and nitro.

The irradiation of conjugated vinyl azides to form the claimed azirenes requires the use of ultraviolet light of a specific wavelength, characteristic of the light emitted by a low pressure mercury lamp. The most effective wavelength of light is 253 m μ (millimicrons) but light of higher and lower m μ values can be used. The suitable ultraviolet light has a wavelength between 200 m μ and 300 m μ . In effecting the useful reaction, nitrogen is evolved and this evolution can be used in estimating the

2

progress of the reaction. When the vinyl azides are irradiated with the proper wavelength of ultraviolet light the rearrangement reaction is substantially complete when the evolution of nitrogen subsides.

The reaction can be most effectively accomplished by dissolving vinyl azides in an inert solvent, such as benzene, toluene, xylene, pentane, cyclohexane, diethyl ether, petroleum ether, octane and other aromatic and aliphatic solvents. The hydrocarbons are especially useful media for conducting the reaction. The resulting azirene is readily separated by evaporating the solvent medium and distilling the concentrated residue.

Further details in the preparation of the described azirene derivatives are set forth in the following examples.

15

EXAMPLE 1

Ethyl β -azidocrotonate (2.60 g., 16.8 mole) dissolved in 100 ml. of benzene was photolyzed with a low pressure mercury lamp at 253 m μ for 18 hours when nitrogen evolution was complete. The solution was concentrated and distilled at 30° C./0.1 mm. to separate 2.0 g. (93%) of a light yellow oil. This oil had strong absorption in the infrared at 4.85 μ (ketenimine) and 5.82 μ and showed two components on G.L.C. (SE 30, 80°) in the ratio 3:1. When this oil was redistilled at 80–90° C./70 mm. the ketenimine band disappeared from the infrared spectrum and the minor component was not present in the chromatogram. The azirene has infrared maxima at ν 5.85 and 8.4 μ with a small peak at 5.6 μ (azirene). The nmr spectrum has signals at 2.2 (one proton spike) and 2.45 δ (methyl spike). The mass spectrum has a major fragment at 54 m/e

N>⊕

Analysis.—Calcd. for C₆H₉NO₂: C, 56.68; H, 7.14; N, 11.02. Found: C, 56.79; H, 7.30; N, 10.90.

This compound was identified as 3-methyl-2-carbethoxy-2H-azirene.

EXAMPLE 2

Nine grams of ethyl β -azido- α -methylcrotonate was irradiated as a 10% solution in benzene for 24 hours with a low pressure mercury lamp at 2.53 m μ . The solution was concentrated and distilled at 95° C./32 mm. to separate 5 g. of azirene. The oil had infrared absorption at 5.7 μ corresponding to the azirene double bond stretch. The mass spectrum was consistent with this structure.

Analysis.—Calcd. for C₇H₁₁NO₂: C, 59.60; H, 7.80; N, 9.94; M.W., 141. Found: C, 59.43; H, 8.01; N, 9.75; M.W., 143.

This compound was identified as 2,3-dimethyl-2-carboethoxy-2H-azirene.

EXAMPLE 3

55 The irradiation of β -azidocrotonamide by the procedure of Example 1 produced a compound identified as 3-methyl-2-carbamido-2H-azirene.

EXAMPLE 4

60 β -Azido-N-methylcrotonamide in benzene solution was irradiated by light of approximately 253 m μ from a low pressure mercury vapor lamp. After 24 hours the nitrogen evolution had ceased. The reaction mixture was concentrated by evaporation of the solvent medium and the residue distilled. The product recovered was identified as 3-methyl-2-(N-methylcarbamido)-2H-azirene.

EXAMPLE 5

70 A compound identified as 3-methyl-2-carboethoxy-2H-azirene was prepared by irradiating p-chlorobenzyl β -azidocrotonate by the procedure of Example 1.

EXAMPLE 6

A chlorobenzene solution of p-nitrophenyl β -azido-crotonate was irradiated with ultraviolet light of 200 to 300 $\text{m}\mu$ for 30 hours. The resulting reaction mixture was topped to remove the residue distilled to recover 3-methyl-2-carbo-p-nitrophenoxy-2H-azirene.

EXAMPLE 7

2 - ethyl-3-methyl - 2 - carbo-3',4'-dibromophenoxy-2H-azirene was prepared by the procedure of Example 6 except that it involved the irradiation of 3',4'-dibromo-phenyl β -azido- α -ethylcrotonate.

EXAMPLE 8

A petroleum ether solution of β -azido β -ethylacryl-amide was irradiated with ultraviolet light $\text{m}\mu$ 253. When the nitrogen evolution ceased the petroleum ether was evaporated and the residue distilled. The product recovered was identified as 3-ethyl-2-carbamido-2H-azirene.

EXAMPLE 9

A diethyl ether solution of β -azido-N-ethylcrotonamide was irradiated by the procedure of Example 1. By evaporation of the solvent medium a product was recovered by distillation and identified as 3-methyl-(N-ethylcarbamido)-2H-azirene.

EXAMPLE 10

The procedure of Example 9 was repeated except the compound subjected to irradiation was dodecyloxy β -azido β -ethylacrylate. The resulting compound was 3-methyl-2-carbododecyloxy-2H-azirene.

EXAMPLE 11

Using the procedure of Example 1 ethyl β -azido- α -phenylbutadienoate was dissolved in ether and irradiated with an ultraviolet lamp $\text{m}\mu$ 253. After the nitrogen evolution was complete the remaining ether was evaporated and the compound formed was identified as having the formula

EXAMPLE 12

Methyl 4-phenyl-3-azidocrotonate was prepared by reacting sodium azide with the methyl ester of 3-benzyl-2,3-butadienoic acid. The subject compound was irradiated by the procedure of Example 1 with ultraviolet light to form 3-benzyl-2-carbomethoxy-2H-azirene.

EXAMPLE 13

Propadienylbenzophenone was dissolved in acetone and treated with sodium azide. The resulting β -azidopropyl benzophenone was dissolved in cyclohexane and irradiated with ultraviolet light. The product recovered from the reaction mixture was identified as having the formula

EXAMPLE 14

Propadienyl ethyl ketone was dissolved in tetrahydrofuran and a mole equivalent of sodium azide was added thereto. The reaction product was dissolved in petroleum ether and the resulting solution irradiated with light from a low pressure mercury lamp. The product recov-

ered from the reaction mixture was identified as 2-propionyl-2H-azirene.

EXAMPLE 15

A toluene solution of p-ethylphenyl β -azidocrotonate was irradiated with ultraviolet light from a low pressure mercury lamp. By continuing the treatment until the nitrogen evolution subsided a substantial yield of 3-methyl-2-carbo(p-ethoxyphenyl)-2H-azirene was recovered.

EXAMPLE 16

Using the procedure of Example 1, 2-azidoallyl p-nitrophenone was treated with ultraviolet light (253 $\text{m}\mu$) until nitrogen evolution ceased. The reaction mixture was distilled and the product recovered was identified as 3-methyl-2-carbo(p-nitrophenyl)-2H-azirene.

EXAMPLE 17

The preceding example was repeated except that 2-azidoallyl 3,4-dichlorophenone was treated with ultraviolet light. The product was found to be 3-methyl-2-carbo(3,4-dichlorophenyl)-2H-azirene.

Although the invention is described with respect to the above specific embodiments it is not intended that the details thereof are to be construed as limitations on the scope of the invention.

The embodiments of the invention in which an exclusive property or privilege is claimed are defined as follows:

1. A compound of the formula

wherein R' is selected from the class consisting of hydrogen, alkyl having up to four carbon atoms, and phenyl; wherein R'' is selected from the class consisting of hydrogen, alkyl of up to four carbon atoms, phenyl and benzyl; and wherein R''' is selected from the class consisting of alkyl having up to twelve carbon atoms, alkoxy having up to twelve atoms, amino, monoalkylamino in which the alkyl moiety has up to four carbon atoms, dialkylamino wherein each alkyl moiety has up to four carbon atoms, the aromatic radicals of the class consisting of phenyl, phenoxy, benzyl, benzoxy and the said aromatic radicals containing substituents selected from the class consisting of alkyl of up to four carbon atoms, chlorine, bromine and nitro.

2. A compound of claim 1 which is 2-carboethoxy-3-methyl-2H-azirene.

3. A compound of claim 1 which is 2,3-dimethyl-2-ethoxy-2H-azirene.

4. A compound of claim 1 which is 2-carbamido-3-methyl-2H-azirene.

5. A compound of claim 1 which is 2-methyl-2-carbamido-3-methyl-2H-azirene.
